US0D1022083S

(12) **United States Design Patent** (10) Patent No.: **US D1,022,083 S**
(45) Date of Patent: ** Apr. 9, 2024

(54) **STRENGTH TRAINING EQUIPMENT**

(71) Applicant: **Shenzhen Shenlaiyibi Technology Co., Ltd.**, Guangdong (CN)

(72) Inventors: **Longfei Wang**, Guangdong (CN); **Hongxu Chen**, Guangdong (CN)

(73) Assignee: **Shenzhen Shenlaiyibi Technology Co., Ltd.**, Guangdong (CN)

(**) Term: **15 Years**

(21) Appl. No.: **29/924,328**

(22) Filed: **Jan. 18, 2024**

(51) LOC (14) Cl. **21-02**

(52) U.S. Cl.

USPC **D21/686**

(58) **Field of Classification Search**

USPC D6/331, 582, 583, 585-598, 591-592; D21/374, 686-688, 798

CPC A63B 69/331; A63B 21/4037; A63B 2210/50

CLAIM

The ornamental design for a strength training equipment, as shown and described.

DESCRIPTION

FIG. 1 is a front, left and top perspective view of a strength training equipment, showing our design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2.

FIG. 10 is another front, left and top perspective view of the strength training equipment in a first usable state; and,

FIG. 11 is another front, left and top perspective view of the strength training equipment in a second usable state.

The broken lines depict portions of the strength training equipment that form no part of the claimed design. The dot-dash broken lines in FIGS. 2 and 9 depict the boundaries of the enlargements that form no part of the claimed design.

1 Claim, 11 Drawing Sheets
